UNITED STATES PATENT OFFICE

JOHN J. REICHERTS, OF DELAWARE, OHIO.

IMPROVEMENT IN BRIDGES.

Specification forming part of Letters Patent No. 175,165, dated March 21, 1876; application filed March 13, 1876.

To all whom it may concern:

Be it known that I, JOHN J. REICHERTS, of Delaware, in the county of Delaware and State of Ohio, have invented a new and useful Improvement in Bridges, of which the following is a specification:

My invention consists of arches formed with cable-wires, the arches being sustained by staves of wood or metal, and the floor-structure being suspended from stirrups, which bind the stayes and the cable-wires together.

Figure 1 is a longitudinal sectional elevation of my improved bridge. Fig. 2 is a transverse section taken on line $\alpha\alpha$ of Fig. 1.

Similar letters of reference indicate corresponding parts.

A represents the arched cable-wires, of which I prefer to use three for each arch, one above another. B represents the staves, forming a body-arch for keeping the cable-arches in position, the latter being applied to the sides of the body. C represents the stirrups, by which the cable-wires and the body-arch

are coupled together and the suspension-rods D are coupled to the arches. E represents keys for taking up the slack of the body-arch from time to time.

The body-arch will be of such depth as will afford the requisite lateral and torsional rigidity. Two cable-arches may be sufficient to each side of the body-arch; but this will depend mainly upon the strength required.

Having thus described my invention, what I claim as new, and desire to secure by Letters Patent, is—

1. The combination of two or more cable-arches, A, with a body-arch of staves, B, substantially as specified.
2. The combination of stirrups C with the arched cable-wires and the body-arch B, substantially as specified.

JOHN J. REICHERTS.
